UNITED STATES PATENT OFFICE.

ANDREW J. HATCH, OF SAN FRANCISCO, CALIFORNIA.

FRUIT-DRIER.

SPECIFICATION forming part of Letters Patent No. 339,767, dated April 13, 1886.

Application filed December 23, 1885. Serial No. 186,574. (No model.)

To all whom it may concern:

Be it known that I, ANDREW J. HATCH, of the city and county of San Francisco, State of California, have invented an Improvement in 55
5 Fruit-Driers; and I hereby declare the following to be a full, clear, and exact description of the same.

My invention relates to certain improvements in apparatus employed for drying fruits 10 and other substances. It is more especially applicable to that class in which a long horizontal chamber is employed having doors or openings at intervals upon the side, through which cars with trays are introduced to be 15 dried and removed when completed.

It consists of a suspended swinging or portable chamber or casing having its inner end fitted to rest against the side of the main chamber, so as to inclose one of the doors of said 20 chamber, and having a door at its outer end, which may be opened to admit a car and be closed behind it before the doors of the main chamber are opened, a means for making a tight joint between the edges of this removable chamber and the sides of the main chamber, and a means for transporting it along by 25 the side of the main chamber, so that it may be applied to any of the doors of said chamber.

Referring to the accompanying drawings 30 for a more complete explanation of my invention, Figure 1 is a perspective view of my device. Fig. 2 is a vertical sectional elevation. Fig. 3 is a horizontal section.

In the construction of fruit-driers I employ 35 a long horizontal drying-chamber having a series of doors upon one side, through which the fruit is introduced in trays, which are preferably supported upon trucks or cars, and rails are laid extending into the chamber at 40 intervals. Upon these many of the cars may be run in, standing side by side, so that their contents may be dried and removed when the work is complete.

In order to prevent great loss by the entrance of a volume of cold air whenever the doors are opened to introduce or remove the cars, I have found it necessary to employ a supplemental chamber, A, which is large enough to receive a car with its load of fruit- 45 trays, and is provided with a door or doors, B, at the outer end. If it were necessary to

have as many of these supplemental chambers as there are doors, it would be very troublesome, and I have devised a method by which a single supplemental chamber may be employed for all the doors in the main chamber and easily transported from end to end of the apparatus, or to any point where it is necessary to use it. In order to do this, I have rails C 55 suitably supported above and to one side of the main chamber, and upon these rails a sort of frame or carriage, D, is fitted to travel on wheels E. From this carriage the chamber A is suspended by chains or loosely-jointed links F, which extend downward from the 60 carriage to each corner of the chamber A. These chains or links are of such length that when the chamber hangs suspended in its usual position it will be drawn against the sides of the main chamber, and held there 65 with considerable force, as the links or chains do not hang quite perpendicular between the carriage and the chamber. The length of the chains is also so determined that when the inner end of the chamber A rests against the side of 70 the drying-chamber the bottom of the chamber A will also rest upon the floor outside of 75 the main drying-chamber.

In order to make a tight joint between the inner ends of the vertical sides and top and 80 the side of the main chamber against which they rest, I fit a strip of rubber or other elastic packing material, G, upon these edges, so that when the casing rests against the side of the main drying-chamber this elastic packing 85 will form a perfectly-tight joint. Similar strips of elastic packing material are fitted along the lower edges of the vertical side pieces of the chamber, and these also rest upon the floor, so as to make a tight joint at this 90 point.

The doors in the sides of the main chamber being closed, when it is desired to introduce or remove a car through any particular door, the supplemental chamber A is brought opposite 95 to that door. If the car is to be introduced, the exterior doors, B, of the supplemental chamber are first opened, the car is run into the supplemental chamber, the doors are closed, and the door of the main chamber is then 100 opened to admit the car. After this has again been closed the supplemental chamber may be

transferred to any desired point. In order to effect this transfer it is necessary to remove the chamber out of contact with the sides of the main chamber and out of contact with the floor. This it will be seen can readily be done, because the suspending links or chains moving about the upper points of suspension as centers when the chamber is drawn back cause it to rise at the same time sufficiently to above the surface of the floor to allow the carriage D to move along its track or tramway to the desired point.

Various devices may be employed to move this chamber back. In the present case I have shown chains or ropes H attached to the inner corners of the chamber and extending to a point where they unite, and a single rope or chain, I, leads from the point of union over a pulley, J, which is attached to the inside of the frame D. The chain or rope I, passing over this pulley, is led back to a lever, K, having its fulcrum upon one side of the frame of the carriage, and, extending across the other side, it is provided with a handle, 25 L, by which it is operated.

M represents a rack upon the side of the carriage, and when it is desired to move the chamber A away from the side of the main chamber, and at the same time raise it from the floor, it is only necessary to move the lever K to one side, thus drawing upon the cord I and the bifurcated cord or chain H, which will thus draw the chamber outward and upward, and the lever K may be held at any desired point by the rack M, so that the carriage D, with its suspended chamber, can be easily moved along the rails. By this construction I am able to employ the single supplemental chamber, and to transport the same

expeditiously from one end to the other of the 40 apparatus. This chamber also serves as a bleaching-chamber, the car-load of fruit being run in and the doors closed while the fruit is submitted to the fumes of burning sulphur, each load being bleached previous to being 45 dried.

Having thus described my invention, what I claim as new, and desire to secure by Letters Patent, is—

1. In combination with the horizontal dry- 50 ing-chamber having doors at intervals upon the sides, through which fruit cars or trays may be introduced, the portable supplemental chamber having exterior doors, substantially as and for the purpose herein described.

2. A suspended swinging supplemental chamber, with its links or chains, in combination with a superposed carriage, from which the chamber is suspended, and a track upon which it travels parallel with the main chamber, 60 substantially as herein described.

3. The carriage supported and traveling upon a line of rails parallel with and to one side of the main drying-chamber, in combination with a supplemental chamber suspended 65 from said carriage by links or chains, and a lever mounted upon the car and having a rope or chain connecting with the suspended chamber, whereby the latter chamber may be drawn outward and upward simultaneously to clear 70 it from the side of the main chamber and the floor, substantially as herein described.

In witness whereof I have hereunto set my hand.

ANDREW J. HATCH.
